FIG. 5.

INVENTOR:
FELIX COUNE

By Jones, Addington, Ames & Rebold
ATTORNEYS.

UNITED STATES PATENT OFFICE.

FELIX COUNE, OF CHICAGO, ILLINOIS.

HAIR-WAVING APPARATUS.

Original application filed January 18, 1924, Serial No. 686,976. Divided and this application filed August 27, 1924, Serial No. 734,538. Renewed April 11, 1927.

My invention relates to improvements in hair waving apparatus, and more particularly to an improved form of bobbin having novel means for attaching hair thereto in a minimum amount of time, and permitting easier manipulation of the bobbin and hair thereon, as well as increasing the beauty and permanency of the wave produced.

10 The present application is a division of my copending application, Serial No. 686,976, filed January 18, 1924, and is directed to that type of bobbin shown therein, wherein tubular sleeve-like members are employed 15 to receive the hair, and scissors-clamps are used to clamp the hair at one end.

A bobbin of this type will be efficient, durable, light and cheap, and may be conveniently and rapidly used.

20 Other objects and advantages will appear from the following detailed description.

In the drawings:

Figure 1 is a view of a device embodying my invention, with clamping members at 25 each end illustrated in open position;

Fig. 2 is a similar view, but illustrating the clamping members in closed position with a tress of hair suitably wound and fastened to the curler or bobbin;

30 Fig. 3 is a detailed view of one of the clamping members held in closed position by means of the hair being wound around a portion of the clamp; and

Fig. 4 is a view taken at right angles to 35 Fig. 3, but with the hair omitted.

Fig. 5 is an alternative embodiment of my invention.

My invention has been designed to overcome the difficulties of holding the hair 40 properly wound on the bobbin. This I have explained in my prior application. It was customary heretofore to tie each end of the hair by short pieces of string to the bobbin. But I have found that it is extremely difficult to tie the hair by string to the bobbin and expect the hair to be perfectly waved when removed from the bobbin.

The essence of the present invention lies in the provision of a design of bobbin having suitable end clamps which facilitate wrapping the hair thereon, and which, at the same time hold the hair in the most efficient position on the bobbin for perfect waving.

By referring to Fig. 1, it will be noted 55 that the curler or bobbin comprises an inner rod of elongated formation which may be made of any desired material. The end of the bobbin, which preferably first receives the tress of hair, is so formed as to provide 60 opposed projections 2. These projections 2 are formed by bifurcating the end after it has been reduced in the manner shown in Fig. 1. A scissors-clamp 3 may be carried by projections 2, the scissors-clamp 3 comprising a pair of pivoted jaw members 4 and 5, between which the ends of hair adjacent the scalp are pressed and clamped. The inner ends of these jaw members 4 and 5 are provided with arms 6, adapted when 70 closed to lie between the projections 2.

At the opposite end of bobbin 1, a second clamp 7 is provided. In view of the fact that each tress of hair may vary in length, it is desirable that clamp 7 should be so 75 mounted upon bobbin 1, that it will be longitudinally adjustable therealong. It is further desirable that this clamp 7 should lie as closely as possible against the bobbin, so that it will not interfere with the insertion 80 of the bobbin within the heating tube. This result may be accomplished by forming clamp 7 out of a pair of jaw members 8 and 9, they preferably being semi-circular in cross section in order to form a concentric 85 sleeve about the bobbin when in closed position.

In order to attain adjustability of clamp 7 along bobbin 1, as just explained, I have provided a plurality of grooves 10 cut in 90 a manner to form transverse shoulders 11. The surface of each groove is formed substantially conical to assist in the mounting of clamp 7, as will be presently described.

The jaw members 8 and 9 are connected 95 together by means of a wire spring 12. Spring 12 may be provided with a coil 13 intermediate the point of connection with jaw members 8 and 9. In mounting clamp 7 on bobbin 1, the coil 13 of spring 12 is forced over the end of the bobbin, the central opening thereof enlarging slightly at the time, by the spreading action resulting in forcing the head 14 at the end of the bobbin through this opening. The coil 13, when engaging 100 in the first groove, will assume its normal size and be prevented from being dislodged by the adjacent transverse shoulders 11.

It will be noted at this point, that coil 13 may be made to engage any of the grooves 10, it depending upon whether it is necessary to bring clamp 7 further down 5 upon the bobbin in order to clamp the end of the hair wound thereon. Spring 12 will tend to hold jaw members 8 and 9 of clamp 7 apart. They may, however, be locked together by the provision of a suitable clip 15 10 on the member 8, the tip of which may engage in a depression 16 in member 9.

The elongated rod is preferably adapted to receive a sleeve-like or tubular member 18, of substantially the same length as the 15 rod. I find it preferable to provide relative movement between tubular member 18 and rod 1, and to serrate or provide a plurality of peripheral teeth 19 at the end of the bobbin receiving the clamp 8. A coil 20 spring 20 may be provided between head 14 of rod 1 and teeth 19, and may be so arranged that end 21 thereof engages the teeth to prevent relative rotation between 25 tubular member 18 and rod 1. Spring 20 further functions to hold tubular member 18 extended toward the opposite end, so that the ends 6 of jaw members 4 and 5 will be held in closed position by lying within the adjacent end of the tubular member. 30 When it is desired to open scissors-clamp 3, the tubular member 18 may be pushed backwardly along rod 1 against the tension of spring 20 until the ends 6 of jaw members 4 and 5 are released.

35 The manner in which the hair will be wound upon the hair receiving portion of tubular member 18, and the manner in which clamps 3 and 7 will fasten the hair at each end of the bobbin are clearly shown in Fig. 40 2. The end of the bobbin carrying clamp 3 is placed on the hair as close to the scalp as possible. After the hair is initially placed between the jaw members 4 and 5, it is then wound once or twice about the 45 arms 6 to hold them in closed position, as illustrated in Fig. 3, and in this manner the scissors-clamp 3 may be held closed. The tubular member 18, however, may be moved backward slightly until the arms 6 are 50 closed by the operator. Releasing the tubular member so that it will move to its original position permits the arms 6 to be confined within the adjacent end of this member. This will hold the hair at this adjacent 55 end of the bobbin while the remaining portion of the tress of hair is wound thereon.

The manner in which the clamp 7 is carried on the opposite end of the bobbin permits it to be quickly mounted. The particular action of clamp 3 and the manner in 60 which it is held in closed position are unique because very little time and effort on the part of the attendant is required, and further because the hair adjacent the scalp is securely held to permit the rest of the tress 65

to be properly wound upon the tubular member 18. This does not require the attendant, or even the person whose hair is being waved to hold the bobbin during the initial securing of the tress of hair thereto, which was 70 heretofore required when short pieces of string were used.

I have found that the coil spring 20 does not interfere with the loop 13 of spring 12, and that loop 13 may be slipped over the 75 head 14 to move to any one of the grooves 10, this being clearly illustrated in Fig. 2.

In Fig. 5, I have shown an alternative embodiment of my invention, the device illustrated being similar in substantially all 80 respects as the device previously described. In this embodiment, however, the tubular sleeve is omitted to permit the hair to be wound directly on rod 1. When fastening the hair to the rod, the inner end of the 85 hair is held by clamp 3 and the clamp is held in closed position in the same manner as it is held closed in Fig. 3, that is to say, the arms 6 of the clamp 3 are closed or moved together to close the clamp and the 90 hair is then wound about the arms 6 to keep them closed.

Various embodiments and modifications of my invention may be made without departing from the spirit and scope of my invention. 95

I claim:

1. A hair curler or bobbin comprising a rod, a tubular member provided with a hair receiving portion surrounding said rod, 100 means for permitting longitudinal movement and restraining relative rotation between said rod and said tubular member, said means comprising a spring attached to said rod and serrations on said tubular member 105 adapted to be engaged by one end of said spring.

2. A hair curler or bobbin comprising a rod, a tubular member provided with a hair receiving portion, and a scissors clamp at 110 one end for receiving the hair before positioned upon said hair receiving portion.

3. A hair curler or bobbin comprising a rod, a tubular member provided with a hair receiving portion, a clamp at one end of said 115 rod for receiving the hair before positioned upon said hair receiving portion, and means for restraining relative rotation between said tubular member and said rod.

4. A hair curler or bobbin comprising a rod, a tubular member provided with a hair receiving portion, and a clamp, said clamp carried by said rod having means adapted to interengage within one end of said tubular member whereby the clamp may be held 120 in closed position.

5. A hair curler or bobbin comprising a rod, a tubular member provided with a hair receiving portion, a clamp on said rod including a pair of pivoted members, and 125

- means for permitting longitudinal movement of said tubular member whereby the adjacent ends of said pivoted members may be confined between one end of said tubular member and said rod to hold said clamping members in closed position. 5
6. A hair curler or bobbin comprising a rod, a tubular member provided with a hair receiving portion, a scissors clamp for receiving the hair adjacent the scalp and for fastening the same to said hair receiving portion at one end, and an adjustable clamp for fastening the hair at the opposite end. 10
7. A device of the class described comprising a rod, a tubular member, and a clamp on said rod and cooperating with said tubular member whereby the clamp may be held in closed position. 15
8. A hair curler or bobbin comprising a rod, a tubular member provided with a hair receiving portion, and a clamp at one end of said rod protruding a distance sufficient from said tubular member to receive the hair and then to be held in closed position by 20
- 25 lying a distance in said tubular member.
9. A hair curler or bobbin comprising a rod, and a scissors-clamp mounted at one end for receiving the hair adjacent the scalp and for fastening the same to the bobbin before it is wound thereon. 30
- 35 10. A hair curler or bobbin comprising a rod, a tubular member provided with a hair receiving portion surrounding said rod, a clamp at one end of said rod protruding a distance sufficient from said tubular member to receive the hair and then to be held in closed position by lying a distance in said tubular member, means for restraining relative rotation between said rod and tubular member, and a clamp at the opposite end for clamping the hair to said tubular member. 40
- 45 11. A hair curler or bobbin comprising a rod, a tubular member provided with a hair receiving portion surrounding said rod, a clamp at each end of said rod for clamping the hair to both ends of said hair receiving portion, and means preventing relative rotation between said rod and said tubular member when the hair is wound upon the latter, said means permitting longitudinal movement between said rod and said tubular member for moving said tubular member over a portion of one of said clamps to 50
- 55 hold it in closed position.
- 60 12. A hair curler or bobbin for receiving a tress of hair wound thereon comprising a rod having a reduced end, a tubular member provided with a hair receiving portion surrounding said rod, clamp members pivotally mounted on said reduced end for fastening the hair to the bobbin and means for extending said tubular member over a portion of said clamping members to hold the latter
- in closed position upon the hair while it is wound upon said hair receiving portion. 65
13. A hair curler or bobbin for receiving a tress of hair wound thereon comprising a hair receiving member, and a pair of clamping members pivotally mounted on said hair receiving member for fastening the hair thereto at one end, a portion of said clamping members being provided for engagement by the hair to hold said clamping members in closed position. 70
- 75 14. A device of the class described comprising a rod, a tubular member longitudinally movable thereon, and a clamp on said rod adapted to be held in closed position when said tubular member is moved forwardly toward said clamp. 80
- 85 15. A device of the class described comprising a central member, a tubular member longitudinally movable thereon, and a clamp disposed at one end of said central member and said tubular member and adapted to be moved to closed position by movement of said tubular member. 90
- 90 16. A device of the class described comprising a central member, a tubular member thereon, and a clamp on said central member adapted to be held in closed position by said tubular member. 95
- 95 17. A device of the class described comprising a central member; a tubular member thereon, and a clamp at one end of said central member having at least one of its legs movably mounted and held in closed position by said tubular member. 100
- 100 18. A device of the class described comprising a supporting member, a clamp carried thereby for receiving a strand of hair, said clamp including a pair of legs relatively movable with respect to each other, and means carried by said supporting member for holding said clamping legs in closed position. 105
- 110 19. A device of the class described comprising a supporting member, a clamp carried thereby for receiving a strand of hair, said clamp having a relatively movable portion, and means on said supporting member for holding said movable portion in closed position. 115
- 115 20. A hair curler or bobbin comprising a rod, a longitudinally movable member surrounding said rod, a clamp at one end of said rod having a portion cooperating with said tubular member upon longitudinal movement whereby said clamp is held in closed position, and locking means at the opposite end of said rod for holding said tubular member in cooperation with said clamp portion. 120
- 125 In witness whereof, I have hereunto subscribed my name.

FELIX COUNE.
